ABSTRACT: An air lock and metering gate valve in which upper and lower arcuate blade-type gates are pivotally mounted on the housing in spaced-apart relation defining a space into which flowable material is admitted and discharged. The gates are operated in sequence so that only one gate is open at any time. Piston motor are direct connected to each of the valve blade arms and the upper blade is spring biased to the closed position to assure that it closes first and opens last. Effective seals are provided for sealing each blade with respect to the valve housing, and a pneumatic piston motor control system permits uninterrupted sequential filling and emptying of the valve housing at adjustable rates.

1
GATE VALVE

BACKGROUND OF THE INVENTION

Air lock type valves are used for discharging and often measuring flowable particulate material, such as powders, grains, chips or the like, into a controlled environment, such as into an area of pressure difference; for example, an air conveying system or the like, where a straight through opening would upset pressures in the system or otherwise would not permit the material to flow. Commonly, rotary gates or rotors having buckets or pockets are employed, requiring close tolerance machining on the side walls and cavity. Where corrosion resistant materials are required, such as stainless steel, the cost of such valves becomes high. Further, in such rotary designs, the edges of the buckets pass through points of shear as many times for each revolution as there are buckets, which causes high power consumption and wear.

SUMMARY OF THE INVENTION

The present invention utilizes blade valve concepts to provide an air lock valve which is simple in design and yet effective in operation. Sheet metal materials may be used for the valve housing, the moving blades, and most other metallic parts. This substantially reduces the cost of the valve over that of designs which use rotary delivery devices.

A valve housing is provided which is generally rectangular in cross section and on which are mounted upper and lower curved blades. These blades each move through suitably sealed openings in one wall of the valve housing into flow permitting and flow blocking relations with respect to the passageway formed through the housing. There is thus defined between the arcuate or curved blades space of controlled and constant volume, and the blades are operated in sequence to fill such space through a top opening and then to permit the discharge of such space through a bottom opening.

A simplified arrangement is provided for operating the blades and includes pivotally mounted blade support arms and fluid pressure operated piston motors which are directly connected to such arms. The piston motors are arranged so that while an opening force is being applied to one arm, a closing force is simultaneously applied to the opposite arm. In this manner, two-way piston motors may be employed for the sequential opening and closing of the valve blades. A spring bias is applied to one of the blades to assure proper sequential operation.

The blades are preferably mounted on arms which are positioned exteriorly of the housing so that they do not interfere with the movement of material within the housing. Further, the blades are each curved arcuately and move along a corresponding arcuate path. The upper blade has its concavity facing downwardly in such a manner that the weight of the material against its upper surface actually assists in the closing of the blade.

Effective seals are provided for each of the valve blades. This includes seals which engage the curved upper surfaces of the blades at the housing sidewalls and seals which engage the upper and lower blade surfaces at the blade slot. The latter seals are preferably mounted exteriorly of the housing and may be readily removed and replaced without the necessity for disassembling the valve.

A fluid motor control system is provided which permits full automatic operation of the valve in a cycle of operation so that the upper blade is first opened to let the material in and then closes before the bottom blade opens to let the material out. A control valve is reversed by the actuation of either one of a pair of pilot valves sensing the open position of each respective blade. The rate of blade movement in a cycle of operation may be accurately regulated by controlling the rate of fluid exhaust from the motors.

The arrangement has several important advantages. First, since fluid pressure is used for actuation, the air lock valve of this invention may be used in an explosive or hazardous en-

2

vironment. Further, it is inherent in the design that the valve is essentially jam-proof, in that oversized or foreign articles will not interrupt the cycle of operation. For example, if a foreign object enters such as to hold one blade partially open, the cycle will continue and on the next cycle, the foreign object will simply fall on through as the blade opening enlarges.

A further advantage is simplicity of construction and the fact that relatively inexpensive materials can be employed as compared to conventional rotary valves. No close machining is required for the parts, such as is required for the sidewalls and cavities of conventional rotary valves. Further the valve of this invention has low power consumption and, for any given size, can handle more material than its rotary counterpart. It can be used for metering and measuring material and for controlling the flow of material even where there is no pressure differential.

These and other objects and advantages of the present invention will become apparent from the following description, the accompanying drawings and the appended claims.

BRIEF DESCRIPTION OF THE DRAWINGS

FIG. 1 is a perspective view of a valve constructed according to this invention;

FIG. 2 is a side elevational view of the valve showing some of the parts in a moved position;

FIG. 3 is a view similar to FIG. 2 but showing the valve from the opposite side;

FIG. 4, 5 and 6 are diagrams showing the sequential operation of the valve;

FIG. 7 is a vertical partially broken away section taken through one valve body showing the details of the upper and lower blade;

FIG. 8 is a fragmentary vertical section taken generally along the line 8-8 of FIG. 7;

FIG. 9 is an enlarged vertical section through a fragment of the rearwall showing one of the blade slot sealing arrangements;

FIG. 10 shows a flange adapter for use of the invention as a substitute for valves using a circular connecting flange; and

FIG. 11 is a simplified pneumatic diagram of the control system.

DESCRIPTION OF THE PREFERRED EMBODIMENT

Referring to the FIGS. of drawing which illustrates a preferred embodiment of the invention, rotary blade air lock valve is illustrated generally at 10 in FIGS. 1, 2 and 3 as including an elongated sheet metal housing or body 12. The body 12 is generally rectangular in section, and defines at its upper end an inlet 13 and at its lower end an outlet 14. The rectangular housing or body 12 may be considered as having a front wall 15, a pair of opposite side walls 16 and 17, and a rear wall 18.

The upper end of the housing 12 at the inlet 13 is formed with a peripheral outwardly extending flange indicated generally at 20. The side portions of the flange 20 extending along the sidewalls 16 and 17 are formed as generally L-shaped bracket members having downwardly depending side flanges 22 engaging the outer surface of the housing side walls. Similarly, the lower end of the body 12 at the outlet 14 is formed with a peripheral mounting flange 25 and upwardly extending flange portions 26 at the sides for attachment to the sides of the body 12.

The valve 10 includes a pair of curved blades which are each pivotally mounted on the housing and are positioned to extend through the rear wall 18 into flow blocking relation to the passage or conduit defined within the housing 12. Thus, the valve includes an upper flow control blade 30 which is preferably formed of sheet material and is rolled or otherwise suitably formed into a true arc or portions portion of a cylinder, with the concavity thereof facing downwardly. The upper blade 30 is pivotally mounted on the housing 12 by means of a pair of external support arms 32, there being one

each of the arms 32 pivotally mounted adjacent each of the sidewalls 16 and 17 respectively. The upper ends of the arms 32 are curved or turned inwardly toward each other at 33 and attached, as by spot welding, to the underneath surface of one end of the blade 30. The lower ends of each of the arms 32 are pivotally mounted on supports 34 extending into the lower flanges 26, as shown in FIGS. 2 and 3.

The radius of curvature defined by the arms 32 substantially equals the radius defined by the blade 30 so that the blade tends to move along a true arc. However, the blade 30 may be arranged to move along an arc which gives the blade camlike upward closing or sealing movement, in the manner disclosed for the blade 25 in U.S. Pat. No. 3,380,475. The blade 30 is formed with a width which substantially equals the width of the housing 12, and has a sufficient length so as to extend in the closed position as shown in FIG. 2 from the inside surface of the front sidewall 15 across the valve and through a suitably formed blade slot 35 formed in the back wall 18 for attachment externally of the housing to the arms 32. While inside arm support for the blade 30 is not disclosed, such may be provided if necessary to support the weight of the material on the upper blade, or for connection in the manner taught in U.S. Pat. No. 3,380,475.

The invention further includes a lower arcuate blade positioned adjacent the valve outlet 14 and mounted for pivotal movement on the housing 12, including a sheet metal blade 40 supported on a pair of arms 42. The blade 40 is formed similarly to the blade 30, and preferably of the same material, and is supported with the concavity thereof facing upwardly. For manufacturing purposes, the blades 30 and 40 may be identical in construction. The arms 42 are pivotally mounted at supports 44 on the upper flanges 22 and are slightly offset so as not to interfere with the movement of the arms 32. The blade 40 extends through a sidewall slot 45 (FIG. 7) in the wall 18 similar to the slot 35 provided for the blade 30. The blades 30 and 40 thus define with the housing 12 an enclosed space of constant or predetermined volume by means of which dry or particulate flowable material may be metered and measured, and emptied through the outlet 14 into an area of pressure difference as compared to that of the inlet 13.

The valve of the present invention further includes fluid-pressure controlled motor means interconnecting the blades 30 and 40 and providing for alternate movement thereof between flow permitting and flow blocking positions with respect to the valve housing, thus providing sequentially for the filling of the defined space within the housing followed by the emptying of material from such space. For this purpose, the motor control means includes a pair of piston air motors 50, one each being positioned adjacent each of the sidewalls 16 and 17, for fully balanced operation of the valve blades.

The piston motors 50 have their opposite ends connected to the arms 32 and 42 in such a manner that when a closing force is applied to one of the blades, an opening force is applied to the other blade. For this purpose, the piston rods 52 are connected at pivotal bushings 53 to the arms 32 at positions between the pivot supports 34 and the blades 30 so that extending movement of the rods 52 applies an opening force to the upper blade 30. At the same time, the clevises 55 of the piston motors are pivotally attached to the arms 42 on rearwardly extending and downwardly offset arm portions 42a. The motors 50 are thus connected to the arms 42 at points remote from the pivot supports 44, so that extension of the motor rods 52 applies a closing force to the blade 40.

The invention includes spring bias means for assuring that the upper blade 30 always closes first and opens last, as compared to the movement of the lower blade 40. For this purpose, a separate tension spring 60 is positioned adjacent each sidewall 16 and 17 of the valve 10, and has one end connected to a binding post 62 and has the other end connected to one of the arms 32 adjacent the pivotal connection 53 of the piston motor 50, and urges the movement of blade 30 into the closed position. The combined force of the springs 60 is sufficient to maintain the blade 30 in the closed position until the blade 40

has been fully closed by the first portion of the stroke of the piston motors 50. Once the blade 40 reaches its closed position, continued extension of the pistons 50 result in the opening of the upper blade 30 against the retractive force of the springs 60. The blades are closed in the reverse manner, the springs 60 assuring that the upper blade 30 closes before the lower blade 40 is permitted to open. Angle iron stop pieces 63 and 64 engage respectively the arms 32 and 42 and define the fully open positions of the blades 30 and 40. The closed position of the blades is defined by the blade engaging the inside surface of the front wall 15.

The valve of the present invention is provided with effective seals for sealing the blades at the slots 35 and 45 as well as for sealing the blades at the sidewalls 16 and 17 of the housing 12. Reference may be had to FIGS. 7 and 8 for details of suitable soft sidewall seals which may be employed in the present invention. Referring first to the sidewall seals associated with the upper blade 30, a pair of plates 70 are received within the housing inlet and retain an elastomeric seal member 72 which has a lower blade conforming edge 73 protruding or extending below the plate 70. The plate is retained in position on the sidewall by a series of screws 74. Since the exposed lower portions 73 of the seals 72 conform generally to the curvature of the upper surface of the blade 30, they engage the upper blade surface in the closed position of the blade and effectively seal the blade at the respective housing sidewalls.

The lower blade 40 may be sealed within the housing in somewhat the same manner, as provided by lower plates 80 which have curved lower surfaces and which support elastomeric seals 82 against the respective sidewalls of the housing. In this case, the lower edges 83 of the seals 82 project below the retaining plates 80 by a short distance and are curved to conform to the curvature of the upper surface of lower blade 40. The upper end 85 of the plates 80 may be curved inwardly toward the sidewall as shown in FIG. 8, to prevent the accumulation of material.

The slots 35 and 45 within the rear wall 18 are preferably fully sealed with seals constructed in the manner shown in FIG. 9. An upper flexible seal 90 extends the width of the slot 35 and is proportioned to extend through the slot into overlying relation with the upper surface of the blade 30. A backup retainer or support 92 extends partially into the slot 35 and prevents the seal 90 from rolling outwardly through the slot during opening movement of the blade. The upper seal 90 is formed with an inner abrupt or sharp edge 94 which engages the upper surface of the blade 32 and, during opening movement of this blade, is in scraping and wiping contact with the upper surface.

An outer upper blade seal 96 is also formed of flexible strap material and extends oppositely to the seal 90 to prevent the entry of air or foreign material into the interior of the housing. The seal 96 extends outwardly of the blade 30 and has a lower end positioned in overlying relation to the upper surface of the blade. A retainer plate 98 removably retains each of the seals 90 and 96 against the outer surface of the rear wall 18 and is accessible from outside the housing for the replacement of the seals, as necessary.

It is also desirable to seal the lower surface of the blade 30 to prevent the escape of the material as well as to prevent loss of pressure differential, and for this purpose, a lower flexible seal 100 extends from a position outside the housing 12 through the slot 35 and engages the lower surface of the blade 30 with a wiping action. Similarly, an outside seal strip 102 extends outwardly of the seal 100 and engages the lower surface of the blade 30. The strips 100 and 102 are retained by an external retaining plate 105, and may be readily replaced without disassembling the valve. The valve wall 18, at the terminal ends of the slots 35 and 45, is provided with outwardly extending tab members 110 which engages the vertical edges of the seals 90, 96, 100 and 102, to provide for a complete seal at the slots and to prevent bypass of material or pressure around the ends of the seals.

The lower blade 40 may be provided with identical seal structure at the slot 45 as described above for the blade 30, and in fact such seal parts associated with each blade are preferably interchangeable with corresponding parts associated with the other blade. While the blade slot seals are preferably located exteriorly of the housing as previously mentioned, it is within the scope of the invention to locate the seals on the inside surface in the manner shown in U.S. Pat. No. 3,380,475. The arcuate inside blade seals 72 and 82 are subject to very little abrasive wear and thus require a minimum of attention.

FIG. 10 illustrates the manner in which the valve may be provided, at each of its inlet and outlet ends, with a circular mounting flange 115. Circular flanges 115 may be provided in lieu of either or both of the rectangularly arranged flanges 20 or 25. In particular, the valve of this invention may be readily adapted as a direct replacement for rotary air lock valves which commonly employ circular mounting flanges of general exterior configuration of the flanges 115. When the valve of this invention is thus employed as a direct substitute for a rotary air lock valve, the capacity provided is usually greater than that of the valve which has been substituted due to the fact that the entire interior of the housing 12 between the plates 30 and 40 is used for measuring and controlling the flow of material through the valve.

The motors 50 may be either hydraulic or pneumatic, as required. Normally, double acting pneumatic motors are preferred since simple open end exhaust systems can then be used, supplied from a low cost air compressor. A suitable valve control system is shown in FIG. 10 as including a two-position, two-way spool-type valve 120. The valve spool may be moved in either of its two selectable positions to apply air under pressure to each of the two-way reversible piston motors 50, and may be constructed according to the teachings of the U.S. Pat. No. 2,586,906 Beckett et al.

The valve 120 is, itself, pressure controlled by air pressure at its opposite ends, and includes internal restrictors 120a which apply air under line pressure to each of the ends of the spool. Thus, if either spool end is exhausted, the spool of the valve 120 will shift toward that end due to the pressure drop across the associated restrictor. Accordingly, the valve may readily be controlled by normally closed, two-position pilot valves 125 connected to each end of the valve 120.

One pilot valve 125 is used for each of the blades, and each of the valves is adjustably positioned on one of the housing sidewalls to be engaged only when its associated arm is in a desired opened position. One valve 125a (FIG. 2) is positioned on the wall 17 to be engaged by an actuator rod 128 forming an extension of the arm 32 when the blade 30 is in a predetermined opened position, resulting in the dumping of pressure from one side of the valve 120 and the shifting of its associated spool with the reversal of application of air pressure to the piston motors 50. The reverse action occurs when the arm 42a engages the pilot valve 125b (FIG. 3). Valve 125b may be adjustably mounted on wall 16, and defines the desired open position of the blade 40.

The pneumatic diagram of FIG. 10 is one in which the valve of this invention will be caused to be cycled in a fully automatic manner as depicted by the views of FIGS. 4, 5 and 6. As shown in FIG. 4, the valve 10 is positioned in flow-controlling relation in a conduit 150 for metering, or controlling the discharge of material while maintaining an air lock, if desired. The upper blade 30 is in the open position and the lower blade 40 is in the closed position, resulting in material being admitted into the interior of the valve. Retracting movement of the motors 50 first results in the closing of the upper blade 30 (FIG. 5) by reason of the superior force of the springs 60 until the upper blade can close no further. Continued retracting movement of the pistons 50 opens the lower blade 40 (FIG. 6) until the arms 42 engage pilot valve 125b. This results in the shifting of the spool within the valve 120, the reversal of air pressure to the motors 50, and the reversal in the sequence of operation depicted in FIGS. 4, 5 and 6 until the position of the

parts as shown in FIG. 4 is attained with the opening of the pilot valve 125a by the rod 128.

The rate of automatic opening and closing of the blades 30 and 40 can be accurately controlled by controlling the rate of exhaust from the piston motors 50. For this purpose, the valve 120 has a common exhaust port 130, and an adjustable restrictor 132 at the port 130 controls the rate of movement of each of the blades by controlling the rate of exhaust from the piston motors. An important advantage of this arrangement is that the valve can thus be accurately regulated and adjusted after installation, and can be "tuned" to the system to obtain the maximum delivery rate or any desired delivery rate less than maximum. In this manner, the weight and flow characteristics of the material being controlled can be accounted for to obtain the greatest use and benefit of the valve by accurately controlling the rate of movement of the blades after installation. In addition, it is within the scope of the invention to provide separate exhaust for both ends of the motors 50 so that the speed of movement in one direction can be controlled independently of the speed of movement in the other direction, where desired.

It is accordingly seen that a versatile, simple, and dependable air lock valve is provided. It is a valve which cannot easily be jammed. For example, if an obstacle prevents the closing of the blade 30, a mechanical force will merely be applied to the blade 40 just as if the blade 30 had reached its predetermined mechanical stop, and the cycle will then continue until the valve 125b is tripped followed by the opening of the blade 30 permitting the obstacle to drop through. The pair of balanced fluid motors 50 in common with each of the blades and associated arms provides equalized forces to each blade, and results in a unit which is reliable and which is low in cost. A single two-position control valve, with only two pilot valves, is effective to provide fully automatic operation with low power requirements and low maintenance cost, and freedom from electrical hazards.

While the form of apparatus herein described constitutes a preferred embodiment of this invention, it is to be understood that this invention is not limited to this precise form of apparatus, and that changes may be made therein without departing from the scope of the invention.

I claim:

1. An air lock gate valve for controlling the flow of particulate flowable material from a first region at one pressure into a second region at a different pressure, comprising an elongated valve housing formed with an inlet adapted to open into said first region, an outlet adapted to open into said second region, said housing defining an enclosed flow conduit extending between said inlet and said outlet, a pair of curved flow control blades including a first blade proportioned to extend across said housing adjacent said inlet in flow blocking relation to said conduit, means on said housing pivotally mounting said first blade with the concavity thereof opening toward said outlet and providing for movement thereof into said flow blocking position and into a retracted flow permitting position, and a second curved blade proportioned to extend across said housing adjacent said outlet in flow blocking relation to said conduit, means on said housing pivotally mounting said second blade with the concavity thereof facing toward said inlet and providing for movement thereof between its said flow blocking position and a retracted flow permitting position for discharging the contents of said conduit stored between said blades, said blades having actuating lever means, a linearly acting motor having two ends each connected to one of said lever means and movable in one direction to urge said second blade into its flow blocking position and simultaneously to cause the first blade to move into its said flow permitting position for admitting material from said first region into said housing conduit, and movable in a second direction to return said first blade to its flow blocking position and with continued movement to move said second blade into its flow permitting position to empty the contents of said conduit into said second region, and bias means to assure that said first

blade closes first and opens last with respect to movement of said second blade.

2. The valve of claim 1 in which said motor means includes a piston motor having its opposite ends connected to apply an opening force to one of said blades and simultaneously a closing force to the other of said blades.

3. The valve of claim 2 in which said first blade is spring biased to a closed position with a sufficient force to assure that its blade closes before said second blade opens.

4. The valve of claim 2 in which said motor means further includes a two-position valve operable selectively to apply fluid pressure to said piston motor to effect alternate opening and closing of said valve blades, and a pair of control valves responsive to the movement of said blades into their respective retracted positions and connected in controlling relation to said two-position valve to reverse the position thereof in response to the movement of either one of said blades into its said retracted position.

5. The valve of claim 5 in which said two-position valve defines an exhaust port through which fluid pressure from said piston motor exhausts during movement thereof, and adjustable fluid pressure relief means associated with said exhaust port for controlling the rate of movement of said blades by controlling the rate of fluid exhaust from said piston motor.

6. A valve for controlling and measuring the flow of particulate flowable material, comprising a valve housing rectangular in section and having an inlet at one end and an outlet at the other end thereof and defining a flow conduit therebetween, a pair of spaced-apart flow control blades each being mounted on said housing and being proportioned to extend through one wall of said housing across said conduit in flow blocking relation thereto with an upper one of said blades being positioned adjacent said inlet and the lower one of said blades being positioned adjacent said outlet and defining therebetween in the flow blocking position thereof a space of predetermined volume, separate lever means being pivotally mounted external of said housing and connected to each of said blades providing for movement of said blades between said flow-blocking positions and a flow-permitting position, bidirectional linear motor external of said housing having two ends each connected to one of said lever means and being operable upon movement thereof in one direction to urge said lower blade toward its said flow blocking position and simultaneously to cause the upper blade to move toward its flow permitting position, and upon reversal thereof first to move said upper blade to its closed position then to urge said upper blade into its closed position while moving said lower blade into its said open position, and bias means to assure that the upper blade closes first and opens last with respect to movement of said blades.

7. The valve of claim 6 in which said one housing wall is provided with a slot for each of said plates, and flexible seal strips mounted on said one wall outer surface adjacent each of said slots and extending through the associated said slot into said housing in overlying relation to the outer surfaces of the associated said blade.

8. The valve of claim 7 further including further flexible seal strips mounted exteriorly of said housing at each of said slots, there being a pair of said further seal strips for each of said blades in which the strips of each said pair are mounted respectively above and beneath an associated said blade and have portions extending outwardly in overlying relation to said blade upper and lower surfaces, and means on said housing one wall extending outwardly away from each said slot at the ends thereof and engaging the ends of said further seal strips for forming with said blade an and said seal strips a complete air lock at said slot.

9. The valve of claim 6 further including arcuate blade seals there being a pair of such arcuate seals for each of said blades received in said housing including an upper seal pair mounted on the inside walls of said housing and having lower surfaces proportioned to engage the upper surface of said upper blade in the closed position thereof and a further said pair of blade

seals having lower surfaces proportioned to engage the upper surface of the said lower blade in the said closed position thereof.

10. An air lock valve for controlling the flow of particulate material comprising, an elongated valve housing being generally rectangular in cross section and having an inlet, an outlet and a flow passage therebetween, a pair of curved blades each being pivotally mounted on said housing and each being proportioned to extend through one sidewall of said housing into flow blocking relation to said passage including an upper blade adjacent said inlet with the concavity thereof opening downwardly and a lower blade adjacent said outlet with the concavity thereof opening upwardly toward said upper blade and defining with said upper blade a space in said housing of predetermined volume, and motor control means interconnecting said blades and providing for alternate movement thereof between flow permitting and flow blocking positions with respect to said passage including a piston motor with one end of said piston motor being connected between one of said blades and its associated pivot point and the other end thereof connected to rotate the other of said blades at a position outwardly of said other blades pivot point for applying an opening force to one of said blades simultaneously applying a closing force to the other of said blades.

20 11. An air lock metering valve adapted to receive flowable dry particulate material from a first pressure region and to transmit a measured quantity of such material to a second pressure region, comprising a generally tubular valve body having an inlet adapted for connection to said first pressure region and an outlet spaced from said inlet adapted for connection to said second pressure region, a valve blade pivotally movable transversely of said body into flow blocking relation to said inlet, a second valve blade pivotally movable transversely of said body into flow blocking relation to said outlet and defining with said first blade an enclosed region in said housing adapted to receive said quantity of material, bidirectional linear actuator means having one end connected in driving relation to one of said blades and having an opposite end connected in driving relation to the other of said blades so that movement of said actuator applies an opening force to one blade and a closing force to the other blade, and bias means urging said first blade into the flow blocking position to assure that it closes prior to the opening of the second blade and remains closed until said second blade is returned to its flow blocking position by said linear actuator.

30 12. A jam-proof automatic flow control valve for measuring quantities of flowable bulk material comprising a valve housing defining a section of conduit having an inlet at one end and an outlet at the other end, a first valve blade adjacent said inlet and movable across said conduit and into a closed flow blocking position and into an open retracted flow permitting position, a second valve blade adjacent said outlet and movable across said conduit into closed flow-blocking and open flow-permitting positions, and in its said flow-blocking position defining with said first blade a space in said conduit for receiving a quantity of said material, a bidirectional fluid pressure operated linear actuator having one end connected in driving relation to said first blade and having another end connected in driving relation to said second blade so that movement of said actuator in either of its two directions applies an opening force to one of said blades and a closing force to the other of said blades, bias means urging said first blade into its flow-blocking position to assure that it closes prior to the opening of said second blade and remains closed until said second blade is returned to its flow-blocking position by said actuator, a fluid control valve operable selectively to apply fluid pressure to said actuator to effect alternate opening and closing movements of said valve blades, and a pair of pilot valves one for each of said blades connected to control said control valve and each positioned to be responsive to the movement of its respective blade only into its open flow permitting position so that a temporary blockage in said conduit preventing the closing of either of said blades does not interrupt the automatic operation of said flow control valve.
